CASTING OF METALS

Gwilym Williams, Quinton, Birmingham,
EnglandApplication June 6, 1934, Serial No. 729,166
In Great Britain June 9, 1933

7 Claims. (Cl. 22—65)

This invention relates to improvements in the casting of metals and refers particularly to the centrifugal casting of articles such as cylinder liner castings, piston-ring pots or any similar articles.

In casting such articles some form of end plate or ring must be secured against the end of the mould during the casting operation to retain the molten metal and must be subsequently removed to allow the casting to be withdrawn. The effective mounting of this end ring is one of the problems in centrifugal casting, and the object of my invention is to provide an improved method of and means for centrifugal casting whereby the usual difficulties associated with the end ring are eliminated and a high rate of output can be obtained with a minimum of labour.

According to my invention in a centrifugal casting machine the front end of the mould during the casting operation is adapted to be partially closed by an end ring capable of moving axially relative to the mould and of swinging out of alignment with the end of the mould. During the casting operation the end ring is drawn tightly against the end of the mould to confine the molten metal and immediately the casting operation is completed the end ring is moved axially out of engagement with the mould and swung up or down or to one side so that it does not interfere in any way with the removal of the casting.

Resilient means are introduced between the end ring and its operating mechanism to allow for axial expansion of the mould.

The axial movement of the end ring is conveniently effected by an axially movable member which is in alignment with the axis of the mould and to which the end ring is coupled by pivoted links, means being provided for bringing the ring into axial alignment with the end of the mould as the ring is drawn against it and for releasing the ring to allow it to swing after it has been moved away from the end of the mould.

My invention is applicable either to a solid mould or to a mould which is divided into parts capable of being forced or held together or separated.

Where my invention is applied to a divided mould the end ring may be controlled by the same mechanism which opens and closes the mould parts, the mechanism, after a casting has been made, first displacing the end ring and then opening the mould parts, and subsequently closing the mould parts and replacing the end ring.

One practical form of my invention as applied

to a solid mould is illustrated by way of example in the accompanying drawings in which:—

Figure 1 is a side elevation of the mould and its mounting with the end ring in place.

Figure 2 is a sectional plan.

Figure 3 is a front elevation and half-section.

Figure 4 is a side elevation in part section of the mounting and operating mechanism.

Figure 5 is a sectional elevation on a larger scale of the left hand end of the mechanism shown in Figure 4.

Figure 6 is a side elevation of one form of means for raising the end ring into alignment with the end of the mould.

In the drawings 1 is a mould suitable for the 15 centrifugal casting of cylinder liner castings. The mould is detachably secured by bolts 2 to carrier arms or brackets 3 projecting forwardly from a face-plate 4 mounted on a rotatable horizontal shaft 15. The carrier arms are provided 20 with substantial radial flanges 5 which not only stiffen the arms but create a considerable windage as they rotate and assist in cooling the mould. The housing 6 in which the end ring 53 is held against the outer end of the mould during the 25 casting operation is carried at each side of the mould by a rod 7 of which the rear end enters a bore in a bracket 8 and is keyed therein by a stud or pin. This mounting permits longer or shorter rods 7 to be substituted for use with 30 moulds of greater or less axial length.

The housing 6 may be fixed to the rods 7 as shown, or may be pivotally mounted on the ends of the rods 7.

Each bracket 8 is carried at the forward ends 35 of a pair of parallel rods 9 of which the rear ends are secured in a bracket 10 pivoted on a horizontal radially extending pivot-pin 11. The pin 11 in turn is carried in a boss 12 secured between the ends of spaced transverse blade, leaf, or plate springs 13 carried by a collar 14 which is axially movable relative to the hollow shaft 15 of the face-plate as best shown in Figure 2. The springs 13 allow for slight axial movement of the end ring 53 as the mould expands.

A yoke 54 which presses against the front leaf spring prevents the resilience of the springs from operating during the forward movement of the end ring when it is being pushed away from the 50 end of the mould.

Positive location of the end ring 53 in axial alignment with the end of the mould is ensured by sloping grooves or keyways 16 in the brackets 8 which engage with the edges of complementary 55

guiding plates 17 adjustably mounted on the carrier arms.

During the making of a casting the parts are in the positions shown in Figures 1 and 2, the end ring 53 being held tightly against the end of the mould while the whole is revolved, and the metal is poured into the mould through the opening in the end ring 53. When the casting has solidified the collar 14 is moved forwardly by the mechanism described below and the end ring 53 is thereby moved axially away from the end of the mould until the brackets 8 clear the guide plates 17 whereupon the end ring swings down under gravity about the pins 11 as pivots, away from the end of the mould, so that the casting can be readily ejected. The ring is then raised again into approximate alignment with the end of the mould and the collar 14 is retracted to draw the ring against the end of the mould, the ring being accurately centered by the guides 17 as it approaches its final position.

The weight of the pivoted assembly carrying the ring 53 may be counterbalanced by springs 18 connected between the rods 9 and the flanges 5 on the carrier arms.

For ejecting the finished casting a plunger or piston 19 is located in the rear end of the mould and is mounted on the front end of a central rod 20 axially movable in the hollow shaft by means of the mechanism described below.

Referring now to Figures 2 and 4 the hollow shaft 15 of the face-plate carrying the whole mould assembly is rotatably mounted in ball or roller bearings in spaced plummer blocks 21, 21 mounted on a suitable bed-plate. A pulley 22 on the shaft receives a belt for driving, and a band-brake 23 is provided for bringing the shaft to rest. Axially slidably within the shaft 15 is an intermediate shaft 24 on the front end of which the collar 14 is secured as shown in Figure 2. Keyed on the shaft 24 at the rear beyond the end of the shaft 15 is a screw member 25 co-operating with an internal thread in a sleeve 26 to which is bolted a hand-wheel 27 mounted on a bush 28 which is rotatable on the shaft 15. Thrust collars 29 take the end thrust between the bush and the shaft 15 and prevent axial movement of the sleeve 26 and hand-wheel 27 so that rotation of the hand-wheel 27 causes axial movement of the screw member 25 with the intermediate shaft 24 and hence of the collar 14 and the end ring 53.

The hand of the thread of the screw member 25 and of the thread in the sleeve 26 is preferably such that as the rotating members are brought to rest by the brake the inertia of the parts tends to cause axial movement of the shaft 24 to release the end ring and as the machine is started again the inertia tightens up the ring against the mould.

For operating the ejector 19 the rod 20 which rotates with the mould is extended rearwardly through the shaft 24, and its rear end is rotatably anchored in an externally screw-threaded sleeve 30 which is axially movable in a stationary sleeve 31 mounted in a bracket 32. A hand-wheel or capstan 33 is bolted to a further sleeve 34 which is rotatable on the sleeve 31 but is held against axial movement by thrust collars 35. The rear end of the sleeve 34 is keyed to a nut member 36 engaging with the screw-threaded sleeve 30 so that rotation of the hand-wheel or capstan 33 and sleeve 34 causes axial movement of the sleeve 30 and hence of the rod 20 and ejector 19. The rotatable coupling between the rod 20 and the sleeve 30 is formed by a ball thrust bearing 37 and a spring 38 interposed between an internal

shoulder 39 in the sleeve and a washer 40 secured on a reduced end of the spindle by lock-nuts 41. The spring 38 allows for expansion of the mould and its mounting. The rear end of the sleeve 30 is closed by a cap 42 which presses against the washer 40 during the ejection of the casting.

It will be understood that the mechanism illustrated and described above for operating the end ring and ejector is representative only, and that rack and pinion or other mechanism may equally well be employed.

Where an end ring in accordance with my invention is applied to a divided mould the opening and closing of the parts of the mould may be effected by the same mechanism which operates the end ring, the sequence of operations being so arranged that after a casting has been made the end ring is first moved away from the mould which is then opened, and after the casting has been removed the mould is closed and the end ring is replaced.

Any convenient mechanism may be employed for raising the end ring again into approximate alignment with the end of the mould after a casting has been removed. One convenient form of mechanism is illustrated in Figure 6. In this case the end ring is adapted to be raised by an arm 43 projecting forwardly from the lower end of a yoke or U-piece 44 pivoted at 45 on fixed supports. The upper end of one arm of the yoke 30 is connected by a link 46 to an arm 47 keyed on a shaft 48 on which is mounted a pedal 49 so that depression of the pedal throws up the arm 43 and raises the end ring into alignment with the end of the mould. The location of the pedal 49 is such that it can be operated by a workman at the same time as the hand-wheel by which the axial movement of the end ring is controlled.

Instead of allowing the end ring to fall by gravity at the end of its axial movement away from the mould, a mechanism may be employed to swing it upwards or sideways, and to bring it back into position preparatory to drawing it back axially against the end of the mould.

If desired any convenient form of guard may be arranged to surround or partially surround the open end of the mould during casting. A suitable form of guard is made of sheet metal and is of horseshoe outline and of channel section with the open face of the channel directed inwardly, the guard being supported by longitudinally extending bars running on rollers at each side of the mould so that it can be readily moved into its operative position during casting and moved out of the way when necessary.

I claim:

1. A machine for the centrifugal casting of metals comprising a mould, a carrier for supporting said mould on a face plate mounted on a rotatable shaft having its axis in alignment with that of the mould, a member movable axially on said shaft, laterally projecting resilient strips mounted on said member, links extending along opposite sides of the mould and pivoted at their rear ends on said resilient strips, an end ring carried at the front end of said links, and means for moving said axially movable member to draw said end ring against the front end of the mould and to move said end ring away from the mould and permit it to swing on the links out of alignment with the mould.

2. A machine for the centrifugal casting of metals comprising a mould, a carrier for supporting said mould on a face plate mounted on a rotatable shaft having its axis in alignment with

- that of the mould, a member movable axially on said shaft, laterally projecting resilient strips mounted on said member, links extending along opposite sides of the mould and pivoted at their rear ends on said resilient strips, an end ring carried at the front end of said links, means for moving said axially movable member to draw said end ring against the front end of the mould and to move said end ring away from the mould and 5 permit it to swing on the links out of alignment with the mould, and co-operating guiding means on the links and mould carrier for guiding said end ring as it approaches the mould, said guiding means being disengaged as the end ring is moved 10 away from the mould.
3. A machine for the centrifugal casting of metals comprising a mould, a carrier for supporting said mould on a face plate mounted on a rotatable main shaft having its axis in alignment 15 with that of the mould, an end ring for partially closing the front end of the mould during a casting operation, an intermediate shaft fitting within and axially movable in the main shaft, screw and nut mechanism for moving said intermediate 20 shaft axially, a collar on the front end of said intermediate shaft, and resilient and pivoted means connecting said collar to the end ring which is drawn against the front end of the mould when the intermediate shaft is moved in 25 one direction and is moved away from the mould and permitted to swing out of alignment with the mould when the intermediate shaft is moved in the other direction.
4. A machine for the centrifugal casting of 30 metals comprising a mold, a carrier for supporting said mould on a face-plate mounted on a rotatable main shaft having its axis in alignment with the mould, an end ring for partially closing the front end of the mould during a casting operation, an intermediate shaft axially slidible in 35 the main shaft, a resilient and pivotal connection between said end ring and said intermediate shaft, a central rod axially movable within said intermediate shaft, an ejector arranged within 40 the mould and mounted on the front end of said rod, and means for moving said intermediate shaft and said rod axially within said main shaft to move said end ring and ejector axially with respect to said mould.
5. A machine for the centrifugal casting of 45 metals comprising a mould, a carrier for supporting said mould on a face-plate mounted on a
- rotatable main shaft having its axis in alignment with the mould, an end ring for partially closing the front end of the mould during a casting operation, an intermediate shaft axially slidible in the main shaft, a resilient and pivotal connection 5 between said end ring and said intermediate shaft, a central rod axially movable within said intermediate shaft, an ejector arranged within the mould and mounted on the front end of said rod, and screw and nut mechanism for moving 10 said intermediate shaft and said rod axially within said main shaft to move said end ring and ejector in one direction to move the end ring away from the mould and eject a casting and to move them in the other direction to retract the 15 ejector and draw the end ring against the end of the mould.
6. A machine for the centrifugal casting of 20 metals comprising a mould, a carrier for supporting said mould on a rotatable shaft having its axis in alignment with that of the mould, a member movable axially on said shaft, an end ring for partially closing the front end of the mould during a casting operation, means connecting said 25 axially movable member to the ring for moving the ring towards and away from the end of the mould, a joint in said connecting means about which the ring can swing out of alignment with the mould when it is moved away from the end of the mould, and positive means for returning the 30 end ring into approximate alignment with the end of the mould after a casting has been withdrawn from the mould.
7. A machine for the centrifugal casting of 35 metals comprising a mould, a carrier for supporting said mould on a face-plate mounted on a rotatable shaft having its axis in alignment with that of the mould, said carrier consisting of arms projecting from the face-plate and having radial flanges which create windage as the mould rotates and assist in cooling the mould, an end ring for partially closing the front end of the mould during a casting operation, a member movable axially on the rotatable shaft, a connection between the end ring and the axially movable mem- 40 ber for moving the end ring towards and away from the mould, and a joint in the connection about which the end ring can swing out of alignment with the mould when it is moved away from the end of the mould.

GWILYM WILLIAMS.
